UNITED STATES PATENT OFFICE.

AARON T. KLOPP, OF OMAHA, NEBRASKA.

LICENSE HOLDER FOR MOTOR VEHICLES.

Application filed November 15, 1923. Serial No. 674,968.

To all whom it may concern:

Be it known that I, AARON T. KLOPP, a citizen of the United States, residing at Omaha, in the county of Douglas and State of Nebraska, have invented certain new and useful Improvements in License Holders for Motor Vehicles, of which the following is a specification.

My invention relates to devices for holding the license cards or certificates which are issued upon registration of a motor vehicle, and which are required to be displayed in the driver's compartment of the registered vehicle. It is the object of my invention to 10 provide a simple and inexpensive holder or container for the purpose stated, the holder being readily attachable to the vehicle by tacks or screws, and serving to efficiently protect the contained license or certificate of 15 registration from mutilation or defacement, while enabling inspection thereof at any time without removal from the holder.

A further object of my invention is to provide a holder or container of this character which is of such weight and thickness as to be readily sent to the registrant by ordinary mail and at the usual letter-postage 20 rate.

In the accompanying drawings Fig. 1 is a 25 front view of a license holder embodying my invention, Fig. 2 is a rear view of the same, and Fig. 3 is a detail section thereof on the line 3—3 of Fig. 1, partially broken away, and upon an enlarged scale whereby 30 to represent the parts as of appreciable thickness.

In carrying out my invention I provide a rectangular envelope made of tough moisture-proof paper, which may be of the grade 40 known commercially as "cover-stock." The front portion or face 4 of the envelope has a large opening 5, the corners of said opening being rounded, and its sides and ends being parallel with the side and end edges 45 of the envelope. The opening 5 is closed by means of a transparent sheet 6 of celluloid or the like, which is placed within the envelope and is sealed to the face 4 about the margin of the opening 5, throughout the area between the edges of the opening and the dotted line 7 in Fig. 1. The sealing of the celluloid sheet to the envelope face is effected by 50 slightly moistening the contacting face with a suitable solvent, such as alcohol, and then pressing the parts together with a heated die having the shape of the dotted outline

7. The frame-like border about the opening 5 in the face of the envelope is preferably printed with a design including the circular markings 8 near the corners, said markings being for the purpose of indicating the points for inserting tacks or screws when fastening the holder to the vehicle on which it is carried. The rear portion of the envelope is formed by the two side-flaps 9 which are overlapped and secured together by adhesive, a closed end-flap 10, and an open end-flap 11. Adjoining the open flap 11 the body-portion of the envelope has a rounded notch therein, as shown in Fig. 2, to facilitate removal of the contents of the envelope. Within the envelope, adjoining the sheet 6, there is placed a single sheet of stiff paper or cardboard 14, having at the end thereof the notch 15, adjacent to the notch 12 of the envelope-back. Said card 14 forms a stiffening or reinforcing member to prevent the bending or folding of the holder, which would be likely to crack or break the celluloid sheet 6. The reinforcing 80 card or member 14 is permanently secured within the envelope by means of a staple or stitching-wire 16 which passes through the same and the sheet 6 near the closed end of the envelope, as shown, said members being 85 stapled or stitched together before their insertion into the envelope and the sealing of the sheet 6 to the envelope-face. The holder is so proportioned as to receive the license certificate 17 and to retain the same in a 90 position such that the reading matter upon the face thereof may be observed through the part of the transparent sheet 6 which is exposed at the opening 5. The staple 16 forms a stop to prevent the license certificate being inserted too far into the closed end of the envelope, and so that the end of the license card or certificate may be grasped at the notches 12—15, should it be desired to remove the same from the holder. 100

It will be seen that the license holder provided by my invention is of such form and weight as to be conveniently sent to the licensee or registrant of the motor vehicle by ordinary mail, by being inclosed in a 105 slightly larger envelope and handled as a letter. The markings 8 indicate, without special instructions to the receiver of the license, the manner in which the holder is to be secured to the vehicle. When in use the open flap 11 is secured at the back of the holder by the tacks or screws which pass

through the adjacent corners, and the inclosed certificate is efficiently protected from mutilation or defacement, while inspection thereof is enabled at any time without re-
moving the certificate from the holder. The inexpensive construction of my license holder, as compared with the metal holders heretofore commonly used, enables a considerable economy in this item of expense to motor vehicle registration bureaus, by whom the license holders are customarily furnished to the licensees or registrants.

Now, having described my invention, what I claim and desire to secure by Letters 15 Patent is:

A license holder for motor vehicles, comprising an envelope of moisture-proof material having an open end-flap and having

an opening at the front thereof, the edges of said opening being slightly spaced from the adjacent edges of the envelope whereby the remaining portions of the face of the envelope comprise a frame-like border about the opening, a sheet of transparent celluloid and a flat reinforcing member disposed within the envelope, said sheet and member each being substantially coextensive with the envelope, the celluloid sheet being sealed to the face of the envelope about the edges of the opening, and a staple securing together said sheet and reinforcing member near the closed end of the envelope, said staple forming a stop to limit entry of an insert between the reinforcing member and the celluloid sheet.

AARON T. KLOPP.
